TYPE CLIP

Carrol T. Potts, Hudson, N. Y.

Application October 28, 1935, Serial No. 47,170

2 Claims. (Cl. 197—36)

The invention relates to a type clip and more especially to a supplementary type mount for striking type arms of typewriters or the like.

The primary object of the invention is the provision of a clip or mount of this character, wherein the same can be engaged about the striking type arm of a typewriter so as to supplement the type as present upon this arm and in this manner enabling one to adopt the style of symbol or type as may be desired for a writing made by such typewriter.

Another object of the invention is the provision of a clip or mount of this character, wherein the same in its structural makeup is novel enabling the auxiliary or supplementary type presenting letters and symbols to be attached with dispatch and security to the striking type arms of a typewriter and avoids the necessity of any change in such arm or the type permanently carried thereby.

A further object of the invention is the provision of a clip or mount of this character, which is extremely simple in construction, thoroughly reliable and effective in its operation, strong, durable, readily and easily applied to and removed from the type arm of a typewriter and inexpensive to manufacture and install.

With these and other objects in view, the invention consists in the features of construction, combination and arrangement of parts as will be hereinafter more fully described, illustrated in the accompanying drawing, which discloses the preferred embodiment of the invention, and pointed out in the claims hereunto appended.

In the accompanying drawing:

Figure 1 is a fragmentary plan view of a striking type arm of a typewriter showing the clip in position holding a supplementary or auxiliary type.

Figure 2 is a side elevation thereof.

Figure 3 is a sectional view on the line 3—3 of Figure 1 looking in the direction of the arrows.

Figure 4 is a sectional view on the line 4—4 of Figure 1 looking in the direction of the arrows.

Figure 5 is a perspective view of the clip or mount.

Figure 6 is a plan view of the blank from which the clip or mount is made.

Similar reference characters indicate corresponding parts throughout the several views in the drawing.

Referring to the drawing in detail, particularly Figures 1, 2 and 3, A designates generally a portion of the striking type arm of a typewriter which is of the ordinary well-known construction

having at its free end and permanently carried thereby a type B, it being usual that such type embodies several alphabetical letters or symbols which protrude as is customary.

The type end 10 of the arm A is of downwardly tapered form having the curvilinear opposite sides 11 and with this end is engaged the clip or mount constituting the present invention and herein-after fully described.

This clip or mount comprises a strap-like body 12 preferably made from spring steel having inherent resiliency and is cut and bent from a form 13 shown in Figure 6 of the drawing. The body 12 is folded on the line 14 to provide the side portions 15 correspondingly shaped to the sides 11 15 of the end 10. One side 15 has an extension constituting a bed wing 16 provided with letter and symbol openings or slots 17 and 18, respectively, which in their shape correspond to the letter and symbol 19, permanently formed by the 20 type B so that such permanent letter or symbol 19 will fit the openings or slots 17 and 18 when the strap body 12 embraces the end 10 in a manner as shown in Figures 1, 2 and 3 of the drawing.

The extension bed 16 has built thereon the side and end cleats 20 and 21, respectively, while the other side portion 15 of the body 12 is formed with a cleat 22 companion to the cleat 21. These cleats 20, 21 and 22 are engaged with an auxiliary 30 type 23, it having protruded lettering or symbols as at 24 which may be of variable conformation or kind from the permanent lettering or symbol formations on the type B.

The auxiliary type 23 has provided therein 35 countersunk shoulders or seats 25 for the cleats 20, 21 and 22 so that said auxiliary or supplementary type 23 will be fixedly held by the clip when embracing the end 10 of the arm A as will be clearly apparent from Figure 3 of the drawing.

The inherent resiliency of the body 12 snugly and securely embraces the end 10 of the arm A while the interfitting of the lettering or symbol protruding from the permanent type B avoids 45 any displacement of the clip or mount when in position upon the arm A.

The auxiliary type 23 may be of any required style of lettering to suit the individual's taste or needs and may include a special group of figures 50 or a border design accordingly to the work to be typed in the use of the typewriter (not shown).

What is claimed is:

1. A clip or mount of the character described, comprising an inherently resilient body for em- 55

bracing a type end of a striking type arm of a typewriter and having a base portion interfitted with type on said arm, an auxiliary type for the body, and means on the body for the fastening of the auxiliary type superimposed upon the said base portion.

2. A clip or mount of the character described, comprising an inherently resilient body for em-

bracing a type end of a striking type arm of a typewriter and having a base portion interfitted with type on said arm, cleats formed on the body and bed portion and an auxiliary type engaged by said cleats and superimposed upon the bed portion.

CARROL T. POTTS.
